[57] CLAIM

The ornamental design for a hanging steamer package, as shown and described.

DESCRIPTION

FIG. 1 is a top front and left side perspective view of a hanging steamer package showing my new design, with the lid member in a half-open position and the hanger members fully extended;

FIG. 2 is a bottom front and left side perspective view thereof;

FIG. 3 is a left side elevational view thereof;

FIG. 4 is a rear elevational view thereof;

FIG. 5 is a right side elevational view thereof; and

FIG. 6 is a top front and left side perspective view thereof, with the lid member in a fully opened position.

FIG.1

FIG.2

FIG.3

FIG.4
